UNITED STATES PATENT OFFICE.

ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

SPOOLER.

SPECIFICATION forming part of Letters Patent No. 760,646, dated May 24, 1904.

Application filed March 14, 1904. Serial No. 197,990. (No model.)

To all whom it may concern:

Be it known that I, ALONZO E. RHOADES, a citizen of the United States, residing at Hopedale, in the county of Worcester and State of Massachusetts, have invented an Improvement in Spoolers, of which the following description, in connection with the accompanying drawings, is a specification, like characters on the drawings representing like parts.

- 10 In a textile-mill the spooling-machines occupy a peculiarly important position with relation to other apparatus, as they give an opportunity for a ready detection of improperly-spun yarn, it being customary to supply each side of a spooler from a certain set of spinning-frames, so that if slack or soft yarn is detected its origin can be traced back from the spooler to the spinning-frame and the fault corrected.
- 20 The improvement of spooling-machines has among other features included bobbin-holders so constructed that the spent bobbins may be readily ejected and directed to a centrally-located belt or traveling conveyer running longitudinally of the spooler to convey the bobbins to a suitable receptacle, said bobbins being received from both sides of the spooler. Such a spooler is convenient in operation; but it is open to several practical objections
- 30 which seriously interfere with well-established mill practice. In the first place it is impossible to keep separate the spent bobbins received by the conveyer from opposite sides of the spooler, so that all the bobbins are mixed together in the receptacle into which they are discharged. Consequently if the bobbins are to be sent back to the frames from which they came, as is highly desirable, a tedious and more or less imperfect sorting must
- 40 be made. When it is remembered that the frames supplying one side of the spooler may be using bobbins a little longer or shorter than the ones used on the frames supplying the other side or if there is some other difference in the bobbins, it will be manifest that great confusion must result from the mixing up by a single belt-spooler. An attendant or tender looks after each side of a spooler, and if

through carelessness or inattention the yarn is not thoroughly spooled off the bobbins the 50 blame cannot be attached to either spooler-tender when both sets of bobbins are mixed together, one tender blaming the other, and vice versa. It is more convenient and much easier for a spooler-tender to cut a small portion of yarn off a bobbin than to wind it off, and although the bobbin is apt to be cut or scored by so doing the tender will thus dispose of the yarn, if possible, when it is thought that the act will be undetected. Scored and 55 cut bobbins make bad yarn; but it is impossible to say which one of the two spooler-tenders is at fault when the injured bobbins are discovered unless the bobbins ejected from one side of the spooler are kept separate from 60 those ejected at the other side. For these reasons the use of spoolers having a central traveling conveyer or belt has been very much restricted notwithstanding the advantages 65 which they undoubtedly possess.

My present invention has for its object the production of a spooler possessing the advantages of the type referred to, but so constructed and arranged that the objections hereinbefore set forth at some length are entirely 70 obviated.

The various novel features of my invention will be fully described in the subjoined specification and particularly pointed out in the 75 following claims.

Figure 1 is a side elevation, broken out between its ends to save space, of a spooler embodying one form of my present invention. Fig. 2 is a transverse section thereof on the line 2-2, Fig. 1, looking toward the left, and 80 Fig. 3 is a diagrammatic plan view showing the relative arrangement of traveling conveyers and the separate receptacles into which the bobbins from each are discharged.

I have herein shown the spooler in its general structure substantially as in United States Patent No. 744,797, the drum-shaft A^X, spool-carriers or spindles S, on which are mounted the spools A', the rods B for the bobbin-holders, the thread-guides t, mounted on the 90 traverse-rods T, oscillating yokes Y, rocker-

arms R, and links d, connecting them with the traverse- rods T, being all substantially as shown in said patent and operating as therein provided for. As is usual in spoolers, the 5 spool-carriers are arranged in two rows, one at each side of the frame, and a series of bobbin-holders is sustained by one of the rods B at each side of the spooler. The bobbin-holders (indicated as a whole at B¹⁰) may be of any 10 suitable construction, they being herein shown as side ejecting-holders, the guards g being mounted in a carrier g', adapted to rock on the overhanging arm g', which is clamped to the rod B. A bobbin-holder of this general 15 character is shown in United States Patent No. 731,617, a slight side movement of the guards serving to eject the spent bobbin from the holder. I have omitted the mangle and the means for effecting the oscillation of the 20 yokes Y to traverse the rods T, as the same forms no part of my present invention.

A counter-shaft N, Fig. 1, is supported in a bracket 1 on the main frame of the spooler and is driven by a belt 2 from the drum-shaft 25 A^x, said counter-shaft having a sprocket 3 thereon which, by means of a suitable chain 4, rotates a second sprocket 5, fast on a short shaft 6 above and parallel to the counter-shaft N. The shaft 6 has a worm 7 thereon in mesh 30 with a worm-gear 8, fast on a transverse drum-shaft 9, suitably mounted in brackets 10 and 11 on the left-hand end of the main frame of the spooler. A pinion n^x, fast on the counter-shaft, meshes with a gear m^x, fast on the usual 35 mangle-shaft M^x, to drive the latter. Like flanged drums 12 are secured to the shaft 9 at its ends outside the brackets, and an endless conveyer or belt 13 is passed around each drum and extended longitudinally along each 40 side of the spooler below each series of bobbin-holders, as clearly shown in Figs. 1 and 2, the opposite turn of each belt being supported on an idler-pulley 14, one of which is shown in Fig. 1 at the right.

45 A bracket 15 is rigidly secured to the spooler-frame and has a horizontal shelf 16, Fig. 1, upon which is mounted a longitudinally-movable arm 17, longitudinally slotted at 18 to receive bolts 19, which clamp said 50 arm to the bracket-shelf 16, and the idler 14 is rotatably mounted on a stud 20, projecting forward from the arm 17. This extensible or adjustable support for the idler 14 maintains the traveler or belt 13 properly taut 55 and is, in effect, a belt-tightener, it being understood that there will be one of such devices for each belt. At its outer end each arm 17 is extended across the turn of the belt, as at 21, and its upper face is inclined 60 or beveled toward the center of the spooler for a purpose to be described.

In order that the belts 13 may get a firm grip upon the drums 12, idlers 22 are provided, mounted on a shaft 23 in bearings 23^x on 65 the brackets 10 and 11, said idlers being lo-

cated quite close to the drums, so that a large portion of the peripheries of the latter will be engaged by the belts. The upper run 13^x of each belt or conveyer 13 forms the traveling bottom of a trough-like receptacle arranged below each series of bobbin-holders, and one receptacle will now be described. 70

The depending flange 24 of the rail S^x has secured to it a plurality of depending hangers 25, each provided with an outturned foot 26, projecting between the upper and lower runs of a belt, downturned toes 27 on the foot receiving between them the lower run of the belt and preventing lateral displacement thereof. (See Fig. 2.) A shallow elongated sheet-metal box, having a high back wall 28, is seated on the feet of the hangers, the back wall rising substantially to the bottom of the rail-flange or apron 24, so that bobbins ejected from the bobbin-holders B¹⁰ 85 cannot fall into the interior of the spooler. An inclined end guard 29 is shown at the left-hand end of the box in Fig. 1, above the drum, to shield the latter and also to direct a bobbin back onto the conveyer should a bobbin 90 be thrown so far when ejected. The upper run 13^x runs in the box, and the front wall 30 of the box is upturned far enough to act as a guide for the outer edge of the belt, as will be clear from an inspection of Fig. 2. 95

Full-bobbin boxes E are mounted on struts A^x on the side frames of the spooler, substantially as in Patent No. 744,797, the boxes extending the length of the frame and at such a height that the rearwardly-inclined top e of each box at its lower back edge closely approaches the front wall 30 of the belt-box described. Such inclined top e forms the front wall of the trough-like receptacle whose traveling bottom is formed by the upper run 13^x of the belt, the back wall of such receptacle being formed by the upright wall 28 and the flange or apron 24. When the bobbins are ejected from the bobbin-holders, they are directed by the inclined tops e of the full-bobbin boxes E onto the belt or conveyer and are thereby carried lengthwise of the spooler to the right-hand end thereof, viewing Fig. 1. As the bobbins pass over the idler 14 they drop from the belt onto the extension 21, Fig. 1, and slide down its inclined face into the appropriate box or other receptacle provided therefor. In Fig. 1 the box or receptacle D is arranged to receive the bobbins from the belt at the nearer side of the spooler, while the box D' receives bobbins from the similar belt on the other side of the spooler. Thus the bobbins are maintained separate from the time they are ejected to the time they are discharged into one of the receptacles D or D', 125 and the bobbins from each side of the spooler can be returned to the particular set of spinning-frames from which they came originally. As the two sets of bobbins are kept separate, it is easy to trace any faulty work in the spin- 130

ning, and each spooler-tender is responsible for the work performed on his own side of the spooler.

In Fig. 1 I have omitted altogether the full bobbin boxes E in order to show clearly the parts of the apparatus located behind them, the arrangement of the boxes E being manifest from the foregoing description in connection with Fig. 2.

10 As the belt-box having the back and front walls 28 and 30 does not extend up to the idler 14, as shown in Fig. 1, (in order to permit adjustment of the belt-tightening device,) a vertical guard-wall 32 is formed on the arm 17 to extend beyond the adjacent end of the wall 28 to a point substantially opposite the center of the idler 14, as shown.

By the construction herein shown ample room is provided for large boxes or receptacles for the spent bobbins, the traverse mechanism and the belts or bobbin-conveyers being located well toward the top of the frame and out of the way of the spent-bobbin boxes, as appears from an inspection of Fig. 1.

25 My invention is not restricted to the particular form of ejecting bobbin-holders herein shown nor to the particular traverse mechanism, as the means for conveying the ejected bobbins to separate receptacles and for 30 maintaining separate the bobbins ejected from the oppositely-located series of bobbin-holders can be used with any suitable traverse mechanism and ejecting bobbin-holders.

Having described my invention, what I 35 claim, and desire to secure by Letters Patent, is—

1. In a spooler, two oppositely-arranged series of bobbin-holders each provided with means to permit ejection of a spent bobbin, 40 separate receptacles to receive the bobbins ejected from the two series of bobbin-holders, and means to receive and convey to said receptacles, and maintain separated during 45 transit, the bobbins ejected from the two series of bobbin-holders.

2. In a spooler, two oppositely-arranged series of bobbin-holders each provided with means to permit ejection of a spent bobbin, separate receptacles located at one end of the 50 spooler to receive the bobbins ejected from the two series of holders, and means to receive and convey longitudinally of the spooler to said receptacles, and maintain separated during transit, the bobbins ejected from the two 55 series of bobbin-holders.

3. In a spooler, two oppositely-arranged series of bobbin-holders each provided with means to permit ejection of a spent bobbin, separate receptacles to receive the bobbins

ejected from the two series of bobbin-holders, 60 and an endless traveling conveyer below each series of holders, to receive spent bobbins ejected therefrom and convey them to one of said receptacles.

4. In a spooler, two oppositely-arranged 65 series of bobbin-holders each provided with means to permit ejection of a spent bobbin, separate receptacles to receive the bobbins ejected from the two series of bobbin-holders, an endless traveling belt below and back of 70 each series of holders, to receive spent bobbins ejected therefrom and convey them to one of said receptacles, and inclined guides to direct the bobbins to the belts.

5. In a spooler, two oppositely-arranged 75 series of bobbin-holders each provided with means to permit ejection of a spent bobbin, separate receptacles to receive the bobbins ejected from the two series of bobbin-holders, an endless traveling belt below and back of 80 each series of holders, to receive spent bobbins ejected therefrom and convey them to one of said receptacles, a full-bobbin receptacle below each series of holders, having a rearwardly and downwardly inclined top ex- 85 tended adjacent to the outer edge of the contiguous belt, to direct the bobbins thereonto.

6. In a spooler, a series of bobbin-holders at each side thereof and provided with means to permit ejection of the spent bobbins, a longitudinally-extended receptacle below each series of bobbin-holders to receive the bobbins ejected therefrom, each receptacle having an upright back wall, an upwardly and forwardly inclined front wall, and a longitudinally-traveling bottom, and a stationary box at the delivery end of each of said receptacles, to receive therefrom the bobbins ejected from the bobbin-holders.

7. In a spooler, a series of bobbin-holders 100 at each side thereof and provided with means to permit ejection of the spent bobbins, a longitudinally-extended trough-like receptacle below each series of bobbin-holders to receive the bobbins ejected therefrom, a longitudinally-extended belt forming by its upper run the bottom of each receptacle, means to operate the belts, to convey spent bobbins to one end of the frame, and a stationary box at the delivery end of each belt to receive the 105 bobbins therefrom.

In testimony whereof I have signed my name to this specification in the presence of two subscribing witnesses.

ALONZO E. RHOADES.
